UNITED STATES PATENT OFFICE.

SYLVESTER VOORHIES, OF ENDERLIN, NORTH DAKOTA.

TELEGRAPH-REPEATER.

1,291,697.

Specification of Letters Patent.

Patented Jan. 14, 1919.

Application filed July 2, 1917. Serial No. 178,270.

To all whom it may concern:

Be it known that I, SYLVESTER VOORHIES, a citizen of the United States, and a resident of Enderlin, in the county of Ransom and 5 State of North Dakota, have invented certain new and useful Improvements in Telegraph-Repeaters, of which the following is a specification.

One object of my invention is to provide 10 a repeater adapted for working either in a main line or with a main and a duplex line.

Another object of my invention is to provide 15 a repeater of such style as to do away with all except main line batteries when used as a repeater in a main line, and to do away with all batteries except the main line batteries and the customary duplex set of batteries when used as a repeater between the main line and a duplex line.

Another object of my invention is to provide 20 in a repeater a line controller to allow either the east or the west operator to take control of the line.

Another object of my invention is to provide 25 improved means of adjustment for the main line armatures.

Another object of my invention is to provide 30 armatures for the instruments that are extremely light, yet of a rigid construction.

Another object of my invention is to provide 35 in a repeater instruments and circuits in such manner that the repeater may be connected in with a minimum number of connections and dispense with the multiple connections necessary in the ordinary type of repeater.

With these and incidental objects in view 40 the invention consists of certain novel features of construction and combination of parts, the essential elements of which are hereinafter described with reference to the drawings which accompany and form a part 45 of this specification.

In the drawings Figure 1 is a diagrammatic circuit showing the wiring of my repeater; Fig. 2 is an enlarged detail of the line control armature; Fig. 3 is an enlarged detail of the main line armatures; Fig. 4 is an enlarged detail of the main line armature adjustment means; Fig. 5 is a section taken on the line 5—5, Fig. 6; Fig. 6 is an end elevation of one of the main line armatures; Fig. 7 is a diagrammatic circuit of the connecting lines; and Fig. 8 is a dia-

grammatic circuit of the duplex operators' 55 instruments connected to the repeater.

For simplicity in following the circuit it is first assumed that the circuit changing switch is positioned as shown in Fig. 1 and that the repeater is then working between 60 two main lines.

After the description of the operation of the repeater as a main line repeater, it will then be assumed that the switch is positioned on its opposite poles and that the repeater is connecting a main line and a duplex line. 65

Main line repeater.

As shown in Fig. 1, W represents the west 70 going main line instrument; E the east going main line instrument; C the line controller; S a four pole double throw switch for changing the circuits from a main line repeater to a half-duplex and a main line 75 repeater.

In Fig. 7, 7 represents the main line battery at the distant west line station, the instruments being omitted for simplicity as their action is well known to all skilled in 80 the art.

Battery current flows from the main line battery 7 through the main line 8 to a connecting post 1.

Looking at Fig. 1, the circuit is from the 85 connection post 1 through wire 9, resistance 10, wires 11 and 12, spring 13, contact 14, armature 15, wire 16, magnet coil 17, wire 18, connection post 2; and referring to Fig. 7, through wire 19 to battery 21' at the main 90 station.

As the west main line battery is grounded at 22 and the central station battery at 23, this completes the circuit and maintains the coil 17, Fig. 1, actuated so long as the west 95 main line is closed.

The armature 15 of the instrument W was considered energized in the foregoing circuit and the energizing of this armature is accomplished with the following circuit: 100

East main line battery 24, which is grounded at 25, as shown in Fig. 7, through wire 26, connection post 4, and looking at Fig. 1, from connection post 4 through wires 27, 28, and 29, through resistance coil 30, 105 wire 31, switch blade 32, wires 33 and 34, spring 35, contact 36, armature 37, wires 38 and 39, switch blade 40, wire 41, magnet

coil 42, wire 43, connection post 3; and looking at Fig. 7, from connection post 3, through wires 44 and 20 to the central line battery 21, which is grounded at 28.

5 It is evident that the magnet coil 17 of the main line instrument E is thus controlled by the contact 14 which is directly in the main line circuit going west, and that the magnet coil 42 is controlled by contact 10 36 which is directly in the main line circuit going east.

Hence if the east operator opens his line, the actuating coil of instrument W will be deenergized, and if the west operator opens 15 his line the actuating coil of instrument E will be deenergized.

Referring to Fig. 3, it is seen that when the armature 15 is released, the contact 51 is made before the contact 36 is broken, a 20 circuit being established which includes both contacts 36 and 51 for a fraction of a second, and this momentary contact controls the actuation of the line controller C, Fig. 1.

Also referring to Fig. 2, it is seen that 25 the compression spring 47 holds the armature 48 in either a right or left hand position so that either contact 49 or contact 50 is at all times made, and that 49 is not opened before the armature 48 is passed its 30 central position, and hence will thereafter be maintained in its right hand position by the spring 47; and likewise when the armature 48 moves to the left, the contact 50 will not be opened until the armature 48 has passed the central point in its left hand motion, and hence its left hand position will be maintained by the spring 47. Also 35 it is to be noted that the make contact will be closed before the break contact is opened.

40 Therefore, whenever the west line instrument is opened and the armature 48 is moved to the right, the contact 50 will be maintained closed and the contact 49 maintained opened until a new circuit has been 45 established. Likewise when the east line instrument is opened and the armature has been moved to the left, the contact 49 will be maintained closed and the contact 50 maintained opened until a new circuit has 50 been established.

As described in the actuating circuit of the coils 17 and 42, the resistances 10 and 55 30 respectively are in series with the coils and the line controller coils CE and CW are actuated by bringing them across these resistances respectively, as shown by the following circuit.

When the west line operator opens his line thereby deenergizing coil 17, the armature 60 37 is drawn backwardly opening contacts 85, 36, and closing contact 51. This contact bridges the coil CW across the resistance 30, the circuit being as follows:

Resistance 30, wire 31, switch blade 32, 65 wires 33 and 34, spring 35, contact 51, wire

52, switch blade 53, wire 54, coil CW, wire 55, contact 56, spring 57, wire 58, wires 28 and 29, to the other side of the resistance 30, thus actuating the coil CW, closing contact 49, and opening contact 50.

70 Contact 49 is bridged across contact 14 as indicated by wires 59 and 60, and contact 50 is bridged across contact 36 as indicated by wires 61 and 62.

The armature 48 which controls the 75 springs 64 and 65 is so arranged with the springs and with contacts 49 and 50 that when the armature moves from right to left contact 49 will be made before contact 50 is broken, and when the armature moves 80 from left to right contact 50 will be made before contact 49 is broken.

The current flowing through the resistance 30, as already traced, passes through 85 contact 36 which we have just seen is opened as the armature 37 is drawn back.

However, the contact 50 is bridged across contact 36 so that the actual breaking of the circuit feeding battery through resistance 30 is accomplished by the opening of the 90 contact 50 after the armature 48 has moved to the left.

The line now being under control of the west operator, the telegraphing is done as usual, and, as readily seen, both coils 17 and 95 42 actuate practically in unison with the contact 36 controlling the actuation of the coil 42.

The actuation of the circuit when the line is under control of the east operator is 100 analogous and hence will need no further description.

Duplex and main line repeater.

When the west operator wishes to take 105 control he opens his line, his own line circuit which is thus opened being exactly as heretofore described when the instrument was used as a main line repeater.

However, in the half-duplex circuit when 110 the coil 17 is thus deenergized the line controller is actuated by bridging the low resistance portion of C'W across the resistance 30', the resistance 30' being included in the duplex line circuit as follows:

115 Battery 66, Fig. 8, wire 67, terminal 5, and referring to Fig. 1, wire 68, switch blade 40, the switch S now being thrown in its right hand position, wires 39 and 38, armature 37, contact 36, spring 35, wires 34 and 120 33, switch blade 32, wire 70, resistance coil 30', wires 71, 28, and 27, terminal 4; and referring to Fig. 8, wire 72, pole-changer coil 73, wire 74, to the other side of the battery 66.

125 To energize the coil C'W it is bridged across the live resistance 30' in the same manner as the coil CW was bridged across the resistance 30 in the main line repeater, and this new bridging circuit is as follows: 130

Resistance 30', wires 71, 28, and 58, spring 57, contact 56, and wire 55 to one side of the low resistance coil C'W from the other side of the coil, through wire 75, switch 5 blade 53, wire 52, contact 51, spring 35, wires 34 and 33, switch blade 32, wire 70, to the other side of the resistance coil 30', thus energizing the controller, closing contact 49 and opening contact 50.

10 The west operator now telegraphs as usual, energizing coil 17 at each closing of the circuit thereby closing contact 36 and as contact 36 is across terminals 4 and 5, Fig. 1, he thus energizes the local circuit 15 running from terminals 4 and 5, as shown in Fig. 8, thus actuating the pole changer 73.

The operation of the pole-changer 73 places positive or negative current from batteries 77 and 78 respectively on the line 79 20 thus actuating the half-duplex set 80 at the distant east station, the current passing through the coil 81 of the duplex at the center station, and as this operation is well known to all those skilled in the art, it will 25 not be further described.

When the distant half-duplex east operator wishes to take control of the line he changes the polarity at his instrument as in the ordinary manner, thereby opening the 30 contact 82 of the center polar relay.

This contact 82 merely puts battery on and off of the terminals 3 and 6, and as the east operator has now taken battery off of 3 and 6 he thereby deenergizes the low resistance coil 42', Fig. 1, which is merely bridged across the terminals 3 and 6.

The actuation of the controller coil CE is now similar to that described in the circuit for the main line repeater in respect 40 to CW.

In this case, however, the coil CE is bridged across the resistance 10, the circuit being as follows:

Resistance 10, wire 11, spring 13, contact 45 83, wire 84, coil CE, wire 52, contact 85, spring 86, wire 87, to the other side of the resistance 10.

In order to make the adjustment of the main line armatures as simple as possible 50 so that adjustments can be readily made by the ordinary operator, the spring 88, Fig. 4, extends outside of the case inclosing the main line instrument, so that the thumb nut 89 is accessible without moving the cover.

55 A lever 90 is hinged on a shaft 91 and a spring 92 serves to maintain it against the end 93 of the thumb screw.

The spring 88 which is hooked to the

armature is attached at 94 to the end of the lever 90 so that by turning out the thumb 60 nut 89 greater tension is exerted on the spring 88 as the spring 92 over balances the spring 88.

For efficient working of an instrument of this class a light yet rigid armature is a 65 necessary feature, and to provide this I form the armature 37 of light Norway iron or other suitable material and turn a flange 95 about its edge as shown in Figs. 5 and 6.

While I have described my invention and 70 illustrated it in one particular design, I do not wish it understood that I limit myself to this construction as it is evident that the application of my invention may be varied 75 in many ways within the scope of the following claims.

Claims:

1. A telegraph repeater comprising a pair of main line instruments, a line controller, an electrical circuit connected therewith for 80 operating said instruments as a main line repeater, an electrical circuit coöperating with said instrument for operating said instrument as a main line and half-duplex repeater, and means associated with said circuits for changing from one to the other of 85 said circuits.

2. A telegraph repeater comprising a pair of main line instruments, a line controller, a circuit co-acting with said main line instruments and said controller for actuating the combined instruments as a main line repeater, a second circuit co-acting with 90 said instruments for actuating said combined instruments as a main and half-duplex 95 line repeater, and means for selecting either of said circuits at will.

3. In a telegraph repeater the combination of a pair of main line instruments and a line controller, circuit connections for the 100 actuation of said controller through said main line instruments, a second circuit including said main line instruments and said controller and including therein terminals, one pair of which is connectible to the local 105 circuit of a half-duplex pole changer, the other pair of which is connectible to the local circuit of a half-duplex polar relay, means for selecting either of said two circuits, said line controller being under control 110 of either main line operator when used as a main line repeater, or under the control of the main line operator and the half-duplex line operator when used as a main line half-duplex line repeater.

SYLVESTER VOORHIES.
